UNITED STATES PATENT OFFICE.

ALEXANDER BETTIS, OF WARRENSBURG, MISSOURI.

ADVERTISING WASH-BOARD.

SPECIFICATION forming part of Letters Patent No. 247,295, dated September 20, 1881.

Application filed April 9, 1880. (No model.)

To all whom it may concern:

Be it known that I, ALEXANDER BETTIS, of Warrengburg, in the county of Johnson and State of Missouri, have invented a new and valuable Improvement in Advertising Wash-Boards; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a front view of my improved wash-board, and Fig. 2 is a vertical central section of the same.

This invention relates to improvements in devices for advertising; and it consists in the device hereinafter claimed.

In the annexed drawings, the letter A designates a metallic wash - board or wash - board plate, upon which are raised letters $a a' a''$, &c., arranged usually in transverse rows on one or both sides, and forming an advertisement. Numbers or characters of any desired form suitable for the purpose of advertisement may be used, and such raised projections form the

rubbing-surfaces on which clothes are to be rubbed for washing. The plate may be cast with the raised letters thereon complete, when it may be provided with legs b , marginal flange c , and transverse rib or flange d above the raised letters, forming, with flange c , a soap-receptacle, or may be stamped out of sheet metal and the plate placed in a wooden or other suitable frame. The advertisement may be of any desired description—as, for instance, the name, residence, and address of a merchant or manufacturer, the description and qualities of any article on sale, and the place where it can be had, and other like matter.

What I claim as new, and desire to secure by Letters Patent, is—

As an advertising device, a wash-board the rubbing-surfaces of which are raised letters or characters indicating the desired advertisement, substantially as set forth.

In testimony that I claim the above I have hereunto subscribed my name in the presence of two witnesses.

ALEXANDER BETTIS.
